UNITED STATES PATENT OFFICE.

WILLIAM E. PATNAUDE, OF STOUGHTON, MASSACHUSETTS

DISPENSING FAUCET.

Application filed May 26, 1926. Serial No. 111,572.

This invention relates to a faucet of the general type used in dispensing liquids from a tank, or other source of supply, more particularly where the liquid is dispensed into a small receptacle, over a counter or the like, and when any drip from the faucet, after it is closed, would be objectionable.

In my prior application filed May 13th, 1925, a construction is described, which is more or less effective in preventing drops of liquid from falling from the faucet after the same has been closed, but this construction sometimes fails to retain the drops and is therefore not as perfectly effective as is desired.

The object of my present invention is to improve said prior construction as to make the same much more effective in preventing the drip, or preventing any drops from falling from the faucet after the valve has been seated.

I accomplish these objects by means of the construction hereinafter described and as illustrated in the accompanying drawing 25 in which:

Fig. 1 is a vertical longitudinal sectional view of a faucet embodying my invention.

Fig. 2 is a side elevation and Fig. 3 is a plan view thereof.

Fig. 4 is a sectional view at line 4—4 of Fig. 2.

Fig. 5 is a sectional view similar to Fig. 1, on an enlarged scale, of the discharge portion of the faucet and

Fig. 6 is a bottom plan view of the discharge end.

As shown in the drawing, the faucet casting comprises a horizontal inlet portion *a*, adapted to be connected to the source of supply and opening into a vertically extending valve chamber *b*, which is closed at its upper end and has a cylindrically shaped, tubular outlet portion *c* removably connected thereto, to permit assembling, and depending vertically therefrom, so as to form a continuation of the chamber. The lower portion of the wall of said outlet portion *c* is tapered inwardly, as it extends downward, forming an upwardly facing valve seat *e*, from which

an annular lip portion *f* depends, the internal surface thereof extending from the valve seat portion at a substantially reduced angle of convergence and the edge of said lip being disposed in a horizontal plane. A valve stem *g* is provided having an internal bore which extends from its upper end and

in which a guiding post *h* is arranged, said post being fixed in the top side of the chamber *b* and depending vertically therefrom so that said stem will be vertically guided on said post. A flange *i* is formed on the upper end of the stem and a coiled spring *j* is arranged on said post and interposed between the upper side of chamber *b* and flange *i*. The lower end of the stem *g* is provided with a head having an annular groove therein in which an elastic valve washer *k* is held in position to be pressed against the seat *e* by the spring *j*. The extreme lower end portion of the stem is formed to provide a cylindrically shaped projection *m*, which depends below the level of the washer *k* and forms a closure for the upper end of the space enclosed by the lip *f* when the valve is seated. The diameter of the projection *m* is somewhat less than the internal diameter of the lip portion adjacent the seat *e*, but greater than this internal diameter at the lower end of the lip portion, the arrangement being such that the lower end of the projection is held in close proximity to the inner surface of the lip portion when the valve is seated, without actually engaging said surface, so as to prevent full action of the spring in pressing the valve washer against its seat, sufficient leeway, in this respect, being provided for yielding and wear of the washer.

With this construction, therefore, a shallow recess will be formed at the extreme lower end of the faucet outlet, the top of which is flat and disposed in a horizontal plane, and the sides of which are undercut, or extend downward therefrom at a slight convergence.

A handle *n* is provided for lifting the valve from its seat; said handle being connected at right angles to a shaft *o*, rotatably mounted in a packing nut *p*, in one side of the inlet portion *a*, said shaft having a right angularly extending arm *q* at its inner end arranged to engage the under side of the flange *i*, so that when the handle is pushed rearward the valve will be lifted from its seat.

The operation is as follows: When the valve has been opened, so that the liquid flows from the outlet, and then is permitted to be reseated, so that the flow past the seat is cut off, the greater portion of the liquid remaining in the recess enclosed by the lip *f* will be discharged with the solid stream.

A large drop will, however, usually be retained in said recess, which will remain suspended from the flat under side of the projection *m*, as indicated in Fig. 5, or may be partly supported by the converging sides of the lip. It is considered that the drop will be primarily supported by the capillary attraction of the relatively large flat horizontal surface of the projection *m*, and also somewhat by the supporting action of the sides of the lip, which incline inward from said surface, and somewhat by air pressure.

The above described construction has been found in practice to be practically perfectly effective in preventing any after drip, or drops from falling from the faucet outlet after the valve has been seated, and to be more effective than the construction of my said prior application.

20 1. I claim:

1. In a liquid dispensing faucet, a depending tubular casing having a discharge port at its lower end, the walls of which terminate at a uniform level, said casing being internally constricted to form an upwardly facing valve seat and constructed to provide a relatively short annular lip depending from said seat and forming the lower end portion of the casing, and a valve vertically movable in said casing to engage said seat and having a flat, circular, horizontally disposed drop-sustaining face at its lower end arranged, when the valve is seated, to effect a sufficiently tight closure of the top portion 35 of the space encircled by said lip, at a level slightly above the level of the edge of the lip, to form a shallow recess adapted to retain undischarged drops of liquid which have passed the valve seat.

40 2. In a liquid dispensing faucet, a depending tubular casing having a discharge port at its lower end, the walls of which terminate at a uniform level, said casing being internally constricted to form an upwardly facing valve seat and having a relatively short annular lip depending from said seat and forming the lower end portion of the casing, said lip being internally tapered from said seat to its lower end, and a valve vertically movable within said casing to engage said seat and having a horizontally disposed drop-sustaining face at its lower end, so arranged that, when the valve is seated, its edge will be held in close proximity to the inner surface of the lip at a level slightly above the level of the edge of the lip, to form a shallow recess adapted to retain undischarged drops of liquid which have passed the valve seat.

45 3. In a liquid dispensing faucet, a depending tubular casing having a discharge port at its lower end, the walls of which terminate at a uniform level, said casing being inter-

nally constructed to form an upwardly facing valve seat and having a relatively short annular lip depending from said seat and forming the lower end portion of the casing, said lip being internally tapered from said seat to its lower end, and a valve vertically movable within said casing to engage said seat and having a cylindrically shaped projection depending below the level of its seating face, said projection having a flat horizontally disposed, drop sustaining face at its lower end adapted and arranged, when the valve is seated, to effect a substantial closure of the upper portion of the space enclosed by said lip at a level slightly above the level of the lower edge of the lip, thereby to provide a shallow recess to retain undischarged drops of liquid which has passed the valve seat.

4. In a liquid dispensing faucet, a depending tubular casing having a discharge port at its lower end, the walls of which terminate at a uniform level, said casing being internally constricted to form an upwardly facing valve seat and having a relatively short annular lip depending from said seat and forming the lower end portion of the casing, said lip being internally tapered from said seat to its lower end, and a valve vertically movable within said casing to engage said seat and having a projection depending from its under side, said projection having a drop-sustaining face at its lower end and being adapted and arranged, when the valve is seated, to effect a substantial closure of said lower end portion of the casing at a level slightly above the level of the lower end of said lip, and to form with said lip a shallow recess adapted to retain undischarged drops of liquid which have passed the valve seat.

5. In a liquid dispensing faucet, a depending tubular casing having a cylindrical discharge spout at its lower end, the walls of which terminate at a uniform level, said casing being internally constricted to provide an upwardly facing valve seat and said spout being internally tapered to its lower end, and a valve vertically movable within said casing to engage said seat and having a cylindrically shaped projection depending from its under side, said projection having a circular drop-sustaining face at its lower end, so arranged that, when the valve is seated, its edge is held in close proximity to the inner surface of the spout, at a level slightly above the level of the end thereof, to form therewith a shallow recess adapted to retain undischarged drops of liquid which have passed the valve seat.

In testimony whereof, I have signed my name to this specification.

WM. E. PATNAUDE.
